JAMES E. HARDING, OF NEW BRUNSWICK, NEW JERSEY, ASSIGNOR TO GULBENKIAN
SEAMLESS RUG COMPANY, OF NEW BRUNSWICK, NEW JERSEY, A CORPORATION OF
NEW JERSEY

SHUTTLE GUIDE FOR LOOMS

Application filed November 27, 1926. Serial No. 151,147.

My invention relates to looms which employ an oscillating lay having a shuttle box on either end of said lay and a shuttle adapted to be reciprocated across the lay from box 5 to box, through the open warp shed of the fabric being woven on the loom.

The principal object of my invention is to prevent the shuttle from being deflected from its course as it leaves the open warp shed, as by such deflection it does not enter the shuttle box but is projected at a terrific velocity clear of the loom, causing both property damage and personal injury to operators, as is well known to textile manufacturers.

To permit variation in the width of fabrics woven on a loom, the distance intermediate the shuttle boxes is maximum, and when a fabric of lesser width is being woven 20 a space between the longitudinal edges of the body of warp threads and the adjacent end of the shuttle box exists, being sufficient to permit the shuttle to be deflected, before it enters the mouth of the box, by the resiliency 25 of the warp threads of the lower level of the open shed. By the use of my invention a guide is provided between the end of the box and the edge of the body of warp threads, thus preventing the said deflection of the 30 shuttle, by guiding it from the open warp shed into the mouth of the shuttle box.

The details of my invention will be fully disclosed hereinafter, reference being had to the accompanying drawings, of which:

35 Fig. 1 is a plan view of sufficient of the elements of a loom to illustrate my invention;

Fig. 2 is an end elevation;

Fig. 3 is a sectional elevation taken on the 40 line 3—3 of Fig. 1; and

Figs. 4 and 5 are detached perspective views of details of my invention.

In the drawing, the loom side frames are illustrated at 1, 1 being connected by a cross 45 member 2. The oscillating lay is illustrated at 3, and comprises arms 4, 4 pivoted to the frame members 1, 1 at 6—6, and connected by a lay beam 7 at their upper ends. A shuttle beam or race 8 is also secured to the arms 50 4, 4 in the usual manner, and is provided

with a shuttle box 9 of usual construction, at each end, comprising a rear wall 10, a front wall 11 and a top wall 12, the race 8 forming the bottom or floor of the shuttle box.

Adjacent the mouth 15 of each shuttle box 9, I provide shuttle guides 16 and 17 respectively. The left hand guide 16 comprises a shoe 18 positioned substantially parallel with the shuttle race 8 and in a plane substantially coincident with that of the top wall 12 of the shuttle box 9, the shoe being flared upward at each end as shown at 19 and 20, under which the shuttle α passes. A lining 21 of leather, rubber, or other similar material is secured to the underside of the shoe 18, for minimizing the wear and jar on the shuttle. The shoe 18 is provided with a vertically extending supporting leg 22 adapted to be secured to the lay beam 7 by 60 means of a bolt 23 and oscillates with the lay 3.

The right guide 17 is formed similar to the guide 16, but does not oscillate with the lay, being provided with a horizontally extending leg 22^a which is secured by bolts 24, 24 to a fixed portion of the loom frame, in the present instance the harness guide 25. The guide 17 does not oscillate with the lay 7 for the reason that when the lay is in the forward or "beat up" position, the guide 17 would strike against the heads of the pile wires (not shown) and for this reason the guide 17 is stationary, occupying a position 75 immediately adjacent the plane of movement 80 of the inside surface of the right lay arm 4, under the lay beam 7. The guide 17 is in correct position to guide the shuttle when the lay is "back", in which position the shuttle 85 is driven across the lay, on the shuttle race 8, by the usual picker arms 14.

I claim:

1. In a loom having a frame, a lay pivoted to said frame, comprising lay arms, a lay beam and a shuttle race, and having shuttle 95 boxes on said shuttle race; a shuttle guide adjacent the mouth of each shuttle box, one of said guides being secured to said lay and the other being secured to said loom frame.

2. In a loom having a frame, a lay pivot- 100

ed to said frame, comprising lay arms, a lay beam and a shuttle race, and having shuttle boxes on said shuttle race; a shuttle guide adjacent the mouth of each shuttle box, a supporting leg on each guide, one of said legs being secured to said lay and the other leg being secured to the loom frame.

JAMES E. HARDING.
